UNITED STATES PATENT OFFICE.

JOSEPH F. HAGGERTY, OF BUFFALO, NEW YORK, ASSIGNOR TO UNIVERSAL GYPSUM COMPANY, OF CHICAGO, ILLINOIS, A CORPORATION OF DELAWARE.

PLASTER BOARD.

Application filed July 23, 1921. Serial No. 487,004.

To all whom it may concern:

Be it known that I, JOSEPH F. HAGGERTY, a citizen of the United States, residing at Buffalo, in the county of Erie and State of New York, have invented a new and useful Improvement in Plaster Board, of which the following is a specification.

This invention relates to improvements in plasterboard of the kind comprising a suitable body of plastic material provided with a covering of sheets of paper or other fibrous material.

Plasterboard has heretofore been made both in molds and by continuous method, by machine or otherwise, in various widths or thicknesses, the plasterboard usually consisting of plaster of Paris or other suitable plastic material which is covered with a fibrous material, such for example as paper. This covering is arranged on the opposite sides or faces of the board and in some cases the edges of the board are also covered. In the case of plasterboard not having the edges covered, considerable difficulty is experienced, due to the fact that the core or plastic filler, when dry and hard, easily breaks or chips out when handled at the factory, while being shipped, and while being erected. Furthermore, the dry core, owing to its brittleness, easily chips out when being nailed, especially since the nailing ordinarily must be done near the edges of the board. In the case of plasterboard now on the market having its opposite edges covered with fibrous material, the adjacent edges of the covering material overlie each other and are held together by such portions of the filler or plastic material as squeezes or flows between the two edges. Board of this type is objectionable because the layer of plastic material between the two edges is very thin and being brittle, is easily broken and falls out, weakening the board at this point, and furthermore, it frequently happens that the plastic material does not flow or squeeze out far enough to secure the edges of the covering material together.

The objects of this invention are to provide a plasterboard of this kind in which the covering material is so arranged as to greatly reinforce or strengthen the edge portions of the plasterboard and protect the same against injury; also to provide improved

means for sealing together the edge portions of the sheets of fibrous material; also to improve plasterboard of this kind in the other respects hereinafter specified.

In the accompanying drawings:

Fig. 1 is a perspective view of a piece of plasterboard embodying the invention.

Fig. 2 is a section thereof on an enlarged scale.

Fig. 3 is a fragmentary perspective view thereof showing the manner in which the plasterboard is nailed to studding or the like.

A represents the body or core of the plasterboard which may be made of plaster of Paris mixed with sawdust, or any other suitable material, and which is entirely covered or enclosed in fibrous material, two sheets B and C being employed in the embodiment of the invention shown in the drawings. Each of these sheets covers a face of the board and extends around the edges thereof and along the marginal portions of the opposite face, the two sheets overlapping at the edge portions of the board in such a manner that these portions of the board will be covered by a double thickness, or two layers of paper or fibrous material. In the construction shown in the drawings, the sheet B covers one face of the board and the opposite sides of the sheet are folded over as shown at b to enclose the edges of the board and to cover the edge or margin portions of the opposite face of the board as shown at b'. The covering sheet C covers the opposite face of the board and the sides of this covering sheet extend around the edge of the board, overlying or covering the edge or side portions of the sheet B. The portions c of the covering sheet extend around the edges of the board and the extreme edge portions c' of the covering sheet extend to the face of the board opposite to the face covered by the body portion of the covering sheet. When the board is pressed by any suitable or usual means, the edge portions c' of the covering sheet are preferably depressed into the face of the board so that these edge portions lie substantially in the same plane as the body portion of the sheet B.

The sheets of fibrous material are preferably placed into contact with the core while the same is wet or in plastic condition, so

that all parts of the sheets contacting with the core are secured thereto when the board is dried. In order to reinforce the edges of the board, however, the portions of the two sheets which overlap one another are preferably placed into contact so that none of the plastic material enters between the contacting portions of the two sheets, and these portions of the sheets are secured together by means of a suitable glue or adhesive. For this purpose a water-proof or water-resisting adhesive, such for example as a solution of casein has been found entirely satisfactory, although obviously many other substances, such as silicate of soda, animal glue or other materials may be used. Fig. 3 shows how my improved board is secured to studding D , to wit, by means of nails or the like d which pass through four thicknesses 20 of paper or fibrous covering material.

By making the board as described, it will be seen that four thicknesses of fibrous material are provided at the point where the edge is nailed, which heretofore has been 25 the weakest part of the board or panel. Since the fibrous material is very much tougher than the core of the board, damage to the board by breaking or chipping of the edges thereof is largely prevented. The strength 30 of the edge portions of the board is further increased by gluing or pasting together the two layers or thicknesses of paper by means of a tough and elastic adhesive, instead of using the brittle plastic material for the 35 purpose of securing these edge portions together, as has heretofore been done. Those skilled in the art recognize that the greater part of the strength of plasterboard is in the paper covering, so that it is obvious that 40 my improved board has very much stronger edge portions than those heretofore made, especially since the adhesive used has a strength equal to or in excess of the fiber strength of the covering material and very 45 much greater than that of the plaster of Paris now used for the purpose of securing together the edges of the fibrous covering material. The double thickness of covering 50 material also protects the board against injury while being handled and shipped.

While the particular arrangement of the sheets of covering material relatively to each other and to the plasterboard as described is desirable, yet it is not intended to 55 limit the invention to this arrangement

of the sheets, since obviously other arrangements may be used to produce plasterboard having reinforced edge portions as described.

I claim as my invention:

1. A plasterboard comprising a body made of plastic material, a sheet of fibrous material secured to each face of said body portion, one of said sheets having its edge portions extending around the opposite edges of said body and along the margins of the 60 opposite face, and the other sheet having its edge portions overlapping the edge portions of said first mentioned sheet and extending around the edges of the board and along the margins of the face covered by said 65 first mentioned sheet, said overlapping edge portions being secured together by an adhesive, whereby the edges and margins of said board are covered by a double thickness of 70 fibrous material. 75

2. A plasterboard comprising a body made of plastic material, a sheet of fibrous covering material secured to each face of said body portion, each of said sheets of covering material having its marginal portions extending around the opposite edges of said body and over onto the marginal portions of the opposite faces of said body and overlapping the corresponding marginal portions of the other sheet, to cover the opposite edges and marginal portions of said 80 body with a plurality of thicknesses of covering 85 material. 85

3. A plasterboard comprising a body made of plastic material, a sheet of fibrous covering material secured to each face of said body portion, each of said sheets of covering material having its marginal portions extending around the opposite edges of said body and over onto the marginal portions of the opposite faces of said body and overlapping the corresponding marginal portions of the other sheet, the overlapping portions of said covering material being secured together by an adhesive. 95 100

4. A plaster wallboard having a composition body with fibrous cover sheets thereon, one of said cover sheets passing about the longitudinal edges of the wallboard to engage the opposite side thereof with the other cover sheet extending beyond the side it covers and with its margins secured to first sheet and their exterior surfaces in the plane of the surface they engage. 105
